UNITED STATES PATENT OFFICE.

AMHERST G. LAMB, OF TORRINGTON, CONNECTICUT; ELLA A. LAMB, OF TORRINGTON,
CONNECTICUT, ADMINISTRATRIX OF SAID AMHERST G. LAMB, DECEASED.

CARBURETER.

1,192,213

Specification of Letters Patent. Patented July 25, 1916.

Application filed October 13, 1913, Serial No. 795,009. Renewed June 19, 1916. Serial No. 104,576.

To all whom it may concern:

Be it known that I, AMHERST G. LAMB, a citizen of the United States, residing at Torrington, in the county of Litchfield, State of Connecticut, have invented certain new and useful Improvements in Carbureters, of which the following is a description, reference being had to the accompanying drawing and to the figures of reference marked thereon:

10 This invention relates to certain new and useful improvements in carbureters, and has for an object the provision of a carbureter which is designed with successively arranged and operated air inlets, the purpose of which is to dilute the fuel supply and produce a mixture of the proper constituency.

Another object of this invention is to provide means for controlling the admission of such mixture to the motor, said means also serving to operate an air inlet valve and the fuel supply valve when it is desired to change the speed of the engine and also when it is desired to quickly develop additional power.

Another object of this invention is the provision of a carbureter capable of a wide range of adjustments, thereby giving greater flexibility and ease when applying and adjusting it to motors of different types and construction.

With these and other objects in view the invention further consists in the arrangement and combination of parts, all of which serve to obtain a maximum efficiency from the fuel used with the slightest amount of expense.

In the drawings: Figure 1 is a top plan view of my improved carbureter. Fig. 2 is a side elevation. Fig. 3 is a vertical sectional view on the line 3-3 of Fig. 1. Fig. 4 is a detached perspective view of the throttle valve controlling the admission of the mixture to the motor, and its connection with an air valve and the fuel supply valve. Fig. 5 is a vertical sectional view taken on the line 5-5 of Fig. 1. Fig. 6 is a detail sectional view of the fuel supply valve in closed position, and Fig. 7 is a similar view with the fuel supply valve in opened position.

In obtaining the maximum efficiency from an explosive fluid for use in explosive motors, it has been recognized that the relative

proportion of air and the fluid must be changed under different working conditions of speed and power. This has been done heretofore by providing air inlets, the arrangements of which have been at convenient positions about the fuel supply valve and the mixing chamber. These air inlets have entered the said mixing chamber in all directions and upon all sides of the fuel supply, and have been principally designed to compact the structure of the carbureter and economize space.

In designing the present invention the successively arranged and operated air inlets have been positioned with great care to produce a continuous flow of air in one direction to dilute the fuel supply and initially used air to a certain mixing point, from whence the commingled particles are presented to the motor without further interruption or molestation from other air supplies or interrupting injections.

Referring to the drawings, the carbureter consists of an oil or fuel supply, the fuel passing therethrough being adapted to be diluted by three distinct sources of admitted air. These air injections will be referred to as the primary, auxiliary and supplementary air inlets. The first named is used initially and serves to produce a mixture capable of ordinary slow speed, or low throttle work. The second named or auxiliary is designed to augment the initial air supply and is controlled through the same means which operates the throttle and the fuel supply. The third named or supplementary is wholly dependent upon the speed attained by the motor. This latter air inlet still further adds to the already diluted mixture and produces a mixture of lean constituency.

The preferred embodiment of my invention consists of a mixing chamber 1 having the outlet 2 which communicates with the manifold or other suitable means provided on the motor. Arranged in alignment with the mixing chamber 1 and outlet 2 is an air compartment 3 having the auxiliary air inlet valve 4 and the supplementary air inlet valve 5 located therein.

Secured to the mixing chamber is the float chamber 6 through which extends a passageway 8 formed by the tubular member 7.

The float 9 is hollow and loosely sur-

rounds the member 7, as shown in Figs. 3 and 5. The upper end of the float is provided with an annular recess into which fits one end of the lever 10. The other end of the lever 10 is connected to the fuel inlet valve 11 by means of a similar annular recess formed upon the valve stem 12. A suitable pivot 13 is provided for the lever 10 and consists of an adjustable post 14 which extends through the top of the float chamber. The screw threaded extension 15 of the said post is held by means of the nuts 16 in a protruding arm 17, which latter is clamped between the mixing chamber and the float chamber, and is held by one of the screws 18 which hold these said sections together. By this construction, it will be readily seen that ample adjustment is afforded the fuel inlet valve, and the relative operation of the float for controlling the same.

Positioned within the tubular member 7 is a hollow tubular connection 19. This connection 19 has communication with the exterior of the tubular member 7 and is preferably terminated in oppositely disposed grooves 20 formed upon the outer sides of the tubular member. These grooves 20 extend well down into the float chamber and serve to direct the fuel into the tubular connection 19. From the passageway in this tubular connection the fuel is directed upwardly through the nozzle 21, which is secured to this connection 19. The upper end of the nozzle 21 is provided with a seat 22 which receives the valve 23. The valve 23 is herein designated as the fuel supply valve and consists of a conical shaped portion 24. An extension 25 continues from the cone portion and fits into the passageway in the nozzle 21. Grooves 26 are provided in this extension 25 through which the fuel is allowed to pass when the cone portion is lifted off its seat.

The purpose of providing a valve of this character is to insure a uniform discharge of the fuel from the nozzle 21 and it will be obvious that because of the centering of the valve 23 the fuel will be sprayed evenly from the nozzle.

Acting in conjunction with the spray nozzle 21 is a Venturi tube 27, the purpose of which is to thoroughly mix the fuel with the primary charge of air. This tube is provided with the lower cone portion 28, the angle, being a true Venturi angle and directed to a point just beneath the upper edge or seat of the spray nozzle. An upper cone portion 29 is also formed in said tube and extends upwardly at the proper Venturi angle. By arranging this Venturi tube in this manner a highly efficient spray of fuel and air is obtained and presented to the mixing chamber at right angles to the line of directions of the additional diluting air.

The valve 23 which controls the fuel sup-

ply consists of a stem which extends upwardly through the mixing chamber. It is screw-threaded within a member 30, which latter is normally positioned within a boss 1^a formed on the mixing chamber. This member 30 is formed with a double screw thread 31 of a suitable steep pitch, the purpose of which will be described presently. Surrounding the upper portion 32 of the member 30 is a collar 33 having an arm 34 and means for clamping said collar about this upper portion 32.

A flange 35 is formed on the member 30 and serves to seat the said member upon the boss 1^a. A locking nut 36 is provided on the stem of the valve and secures the valve in its desired position when once adjusted. By this construction it will be seen that any movement imparted to the arm 34 will, when the collar 33 is securely clamped to the member 30, rotate the member 30 and its other parts as a unit, and because of the steep threads thereon lift the valve 23 off of its seat, thereby allowing the fuel to pass through the Venturi tube together with the primary air drawn in.

To adjust the fuel supply valve, the valve is screwed down on its seat through the member 30. This member 30 is normally positioned within the boss 1^a so that the flange 35 rests thereon. The arm 34 is then moved to its farthest position as shown in Fig. 1 until stopped. The collar is then clamped around the member 30 so as to turn with it. The lock nut is now forced down upon the collar 34. When in this position, it will readily be seen that a movement of the arm in a counter-clockwise direction as viewed in Fig. 1 will rotate the member 30 and because of the steep threads thereon cause the valve to lift from its seat and admit the fuel.

Should a greater amount of fuel be desired the lock nut may be loosened and the valve opened, when it is again locked. In this latter position the fuel supply valve is normally open to admit a small amount of fuel. The primary air inlet acts in conjunction with the fuel and produces a mixture for ordinary work.

The throttle valve 37 is located near the outlet of the mixing chamber, and is connected to the fuel supply valve through the link 38 which is pivoted to the end of the arm 34 and swiveled in the upper end of an adjustable post 39. This post is adjustable in a block 40 which is secured to the cross shaft 41 by a set screw 42. To this shaft is fastened the throttle valve 37. A set screw 41^a holds the post in its adjusted position. Upon the opposite end of the cross shaft 41 is secured a lever 43 with a suitable connection 44 to the operator of the throttle.

Connected to the throttle valve 37 and the fuel supply valve 23 and adapted to operate

therewith is the auxiliary air valve 4. This connection comprises a post 46 adjustably mounted within the block 40 by the set screw 47. Swiveled to the upper end of the post 46 is the connection 48, consisting of right and left threaded rods 49 and the turn buckle 50. One of the rods 49 is swiveled to an arm 45 extending from the auxiliary valve 4. The auxiliary valve operates in conjunction with a covering plate 51 secured to the chamber 3.

Openings 52 are provided in the valve 4 which is in the form of a disk, and are adapted to register with corresponding openings 53 in the cover plate 51. Any oscillation of the valve 4 will either open or close the openings through which the auxiliary air is admitted, as will be readily understood and later more fully described. This auxiliary valve 4 turns about the stem 54 which is slidably positioned in bearing supports 55 at the upper and lower side of the air chamber 3. Stay bolts 56 extend through the chamber and hold the respective supports and other attending mechanism in assembled position.

The supplementary air valve 5 is arranged on the lower side of the air chamber 3 and is adapted to lift by reason of the suction 30 created in the cylinder of the motor when a certain speed is reached. A spring 57 regulates the tension to be placed upon this valve, said spring being adjusted through the screw 58 and locking nut 59 to secure this 35 tension. The stem 54 to which the supplementary valve is secured moves upwardly through the spring and adjusting nut when suction is produced in the motor. A valve 60 is positioned within the chamber 1 and 40 serves to aid in starting when the air to be admitted is cold.

In adjusting the carburetor, the source of fuel supply or fuel supply valve 23 is first positioned on its seat, the collar 23 carrying 45 the arm 34 having been clamped around the member 30, as hereinbefore described. The post 39 with its link connection is then adjusted in the block 40; a lowering of the post reducing the distance of travel of the arm 34 and consequently the member 30 in lifting the fuel supply valve, and the elevating thereof, increasing the path of travel of said arm and the member 30. The post 46 with its rods and turn buckle connections to 55 the auxiliary valve, is now adjusted in the block 40, a lowering of the post causing the openings in the valve 45 to register with its corresponding openings in the cover plate but for a very short distance. The auxiliary air inlet in this position is consequently small. In elevating the post a greater throw is imparted to the auxiliary valve 45 and a larger amount of air is admitted. When the correct throw has been attained, the 65 turn buckle is then operated to bring the

valve back to its initial position when the throttle valve is moved all the way back. Thus it will be seen that any number of the most minute adjustments may be effected through these connections in obtaining the 70 richest or the most economical mixture.

As the throttle valve 45 is moved through its connections 44, the cross shaft 41 is turned. When this shaft is rocked the block 40 secured to the opposite end imparts 75 movement to the posts 39 and 46, and these latter through their respective connections, to the fuel supply valve and the auxiliary air supply valve, respectively, produce an operation of all these parts in unison 80 through the moving of the throttle lever connections. Therefore, it will be apparent that an increase of fuel supply will be immediately augmented by an additional air supply, other than the primary charge of air 85 taken in initially, and, that a continued increase of the fuel will proportionally produce a corresponding proportionate amount of air and, therefore, a more homogeneous mixture automatically.

When a certain speed has been attained the supplementary air valve is brought into operation and further augments the mixture to the highest possible degree of efficiency.

By arranging the auxiliary and supplementary air inlets upon one side of the mixture as it is initially presented, and positioning the mixing chamber and its outlet so as to receive air in alignment therewith from the said additional air inlets, a more homogeneous mixture is produced, the efficiency and extreme economy of which are highly advantageous.

Thus it will be obvious that the herein-described carburetor is capable of meeting 105 the efficiency demands in this art and at the same time with a minimum consumption of fuel.

Having thus fully described my invention, what I claim is:

1. A carburetor including in combination a mixing chamber, a source of fuel supply, an air passage surrounding said fuel supply, an outlet for said mixing chamber, and means for augmenting the combined fuel 115 and air, including a plurality of air inlet valves arranged upon one side of said fuel supply so as to direct the air in alignment with the outlet and at right angles to the fuel supply.

2. A carburetor including in combination a chamber provided with an outlet, a source of fuel supply for the explosive mixture delivering to said chamber, a controlling valve for regulating the flow of said mixture to said outlet, means connected to said controlling valve for automatically admitting additional fuel and additional air to said mixture at right angles to each other, and means operating independent of said 130

- controlling valve for admitting still further additional air to said mixture, so as to direct the additional air in alinement with the outlet and at right angles to the fuel supply.
5. 3. A carbureter including in combination a mixing chamber provided with an outlet, a source of fuel supply for the explosive mixture delivering to said mixing chamber at right angles thereto, a controlling valve 10 for regulating the flow of said mixture to said outlet, an air inlet valve arranged to one side of said mixing chamber for admitting air in alinement with the outlet and at right angles to the fuel supply, and means 15 including connections between the source of fuel supply, controlling valve and said air inlet valve whereby the ~~several~~ parts are moved simultaneously for proportionately augmenting the mixture.
20. 4. A carbureter including in combination a mixing chamber provided with an outlet, a source of fuel supply for the explosive mixture delivering to said mixing chamber, a controlling valve for regulating the flow 25 of said mixture to said outlet, and means including a plurality of valved controlled air inlets arranged to present the air in alinement with said outlet in said mixing chamber and to one side of the fuel supply for 30 augmenting the explosive mixture.
5. A carbureter including in combination a mixing chamber provided with an outlet, a fuel supply valve for the explosive mixture delivering to said mixing chamber, a 35 controlling valve for regulating the flow of said mixture to said outlet, a valve controlled air inlet arranged to one side of said mixing chamber above the fuel supply valve for delivering air in alinement with the outlet and 40 at right angles to the fuel supply, and means
- including adjustable connections between the fuel supply valve, controlling valve and valved controlled air inlet for proportioning the quantity of air and fuel desired.
6. A carbureter including in combination 45 a mixing chamber provided with an outlet, a source of fuel supply for the explosive mixture delivering to said mixing chamber, comprising an inlet nozzle and valve arranged within an air passageway, said nozzle 50 having communication with a Venturi tube for commingling the particles of the explosive mixture and air, a controlling valve for regulating the flow of said explosive mixture to said outlet, and means connected 55 to said controlling valve for admitting additional fuel and additional air to said mixture.
7. A carbureter including in combination 60 a mixing chamber provided with an outlet, a source of fuel supply for the explosive mixture delivering to said mixing chamber, consisting of a float chamber, an air passageway through said chamber formed by a member separating the float chamber from 65 said air passageway, a nozzle arranged in said air passageway and having communication with the float chamber, and a valve for said nozzle, a controlling valve for regulating the flow of said explosive mixture to 70 said outlet, and means connected to said controlling valve for admitting additional fuel and additional air to said mixture.

In testimony whereof, I affix my signature, in the presence of two witnesses.

AMHERST G. LAMB.
